PCT Search Report dated Jul. 16, 2015, International Application No. PCT/US15/25757.

Primary Examiner — Karen S Acker*Assistant Examiner* — Wendy Arminio(74) *Attorney, Agent, or Firm* — Erin Collins**CLAIM**

The ornamental design for a wipes dispenser container lid, as shown and described.

DESCRIPTION

FIG. 1 is an exploded perspective view of the wipes dispenser container lid shown in FIG. 2 positioned for assembly upon a container base drawn in broken lines.

FIG. 2 is a top perspective view of the wipes dispenser container lid.

FIG. 3 is a bottom perspective view, thereof.

FIG. 4 is a top plan view, thereof; and,

FIG. 5 is a bottom plan view, thereof.

The container base and wipes shown in broken lines in FIG. 1 illustrate the environment and form no part of the claimed design. The broken lines on the wipes dispenser container lid in all the figures depict portions of the article that form no part of the claimed design.
